UNITED STATES PATENT OFFICE.

EMIL O. H. POEPPEL, OF CHICAGO, ILLINOIS.

RADIATOR RELIEF VALVE.

Application filed May 20, 1926. Serial No. 110,450.

The present invention relates to radiator relief valves and has for its principal objects the provision of certain novel constructional features in connection therewith, and more particularly the invention resides in interposing a spring between the thermostatic element and the valve, whereby distortion of the thermostatic element is prevented when the valve becomes seated but further expansion of the thermostatic element continues; the providing of an adjustment screw at the bottom of the valve housing for vertically adjusting the normal position of the thermostatic element; the providing of means for guiding the vertical movement of the thermostatic element during its expansion and contraction; the providing of means for centering and locking the adjustment screw with the thermostatic element; the providing of a dust cap for the valve's air outlet, whereby dust that may enter the ports of the cap is deflected from entering the air outlet; the providing of novel means for swedging the body portion of the valve housing to its nipple or neck portions; and the provision of means for readily converting steam radiator systems into vacuum systems.

These and any other objects hereinafter appearing may be attained by the illustrated embodiment of the structure hereinafter particularly described in the body of this specification and illustrated in the accompanying drawings, in which:

Figure 1 is a view of the valve in section.

Fig. 2 is a sectional plan view taken on line 2—2 of Fig. 1.

Fig. 3 is a sectional plan view taken on line 3—3 of Fig. 1.

Fig. 4 is a sectional view of means for swedging a nipple or neck portion to the body or housing portion of the valve.

Fig. 5 is a sectional view of a modified construction showing a dust cap covering the air outlet of a steam radiator relief valve.

Fig. 6 is a sectional view similar to Fig. 5, showing a device adapted to replace the dust cap, thereby converting the ordinary steam system into a vacuum system.

In the drawings, a radiator relief valve is shown comprising a housing having a dome-shaped head portion 1 and a bell-shaped base portion 2. The head portion has a vertically projecting tubular neck 3 swedged thereto, which comprises the air outlet 4.

The upper portion 5 of the tubular neck's bore is diametrically greater than its lower portion. A gravity operated valve 6 in the larger portion of the bore is adapted to seat 60 therein and close the air outlet against the inflow of air when the steam pressure drops below atmospheric.

An internally screw-threaded dust cap 7 is screwed to the air outlet neck and is provided with ports 8 adjacent the outer edge of its top. These ports do not register with the air outlet and any dust that may enter the ports is thus deflected from entering the air outlet. 70

The base portion of the housing has a nipple 9 swedged thereto and is adapted for connection to the radiator, not shown. A helical spring 10 is interposed between the telescoping flange-headed tube 11 and the tubular thermostatic element 12. An inverted hood 13 has a rod 14 swedged thereto which vertically projects above, and depends from, its head. The depending portion 15 thereof telescopes with the flange-headed tube and the projecting portion is a needle valve 16 which is adapted to close the air outlet during the vertical expansion of the thermostatic element. The hood 13 serves to guide the valve and is shaped like the floats common to radiator valve structures of this class. If water should flow into the device sufficiently to lift the hood, due to the trapped air therein, the valve would accordingly be closed and prevent the escape of 90 water.

A cupped ferrule 17 embraces the lower end of the thermostatic element and has a radially disposed keyhole slot 18, the smaller aperture 19 registering with the bore of the 95 thermostatic member, and the larger aperture 20 being offset therefrom. An adjusting screw 21 through the base of the housing is adapted to adjust the normal position of the thermostatic element. The adjusting 100 screw has an annular groove 22 intermediate its ends and above its screw threads 23, which is adapted to pass through the offset portion of the ferrule's larger aperture and be centered in the smaller aperture at the 105 groove. The head of the adjusting screw telescopes with the bore of the thermostatic element.

The cupped ferrule has a plurality of radially disposed outwardly projecting 110 tongues 24 which are adapted to slidably engage the inner side of the hood and space

the same with respect to the thermostatic element during the inter-relative movement between the hood and the thermostatic element.

6 The adjusting screw 21 passes vertically through the sleeve 25 which is swedged to the base of the housing. The sleeve is internally screw-threaded adjacent its upper end to receive the adjusting screw and externally screw-threaded adjacent its lower end to receive the stuffing box 26 which embraces the adjusting screw.

15 The nipples or necks have annular shoulders 27, and flanges 28 disposed at right angles thereto and co-axial with the nipples or necks. In swedging the nipples or necks to the body or housing, the nipples or necks are inserted into the apertures which they are intended to fill, force being employed to retain the shoulder against, and in correct juxtaposition with the walls of the body or housing. The flange portions on the nipples or necks are then curled by force into gripping engagement with the body or housing. This operation is probably best understood from Fig. 4, wherein the flange portion is shown before it is curled, the dotted lines 28" indicating the position of the flange after the swedging operation is completed.

20 It is obvious that said shoulders might be in the form of a plurality of radially disposed lugs and that said flange might be split to form a plurality of radially disposed tongue, either or both of which would serve the purpose intended by said shoulder or said flange.

25

40 In the modified construction shown in Figures 5 and 6, the usual dust cap for the air outlet of steam radiator relief valves is replaced by a device whereby the steam radiator system is converted into a vacuum system.

45 The converting device comprises a tubular nipple designated generally 29 having a contracted externally screw threaded neck 30 covered by a dust cap 31. The base portion 32 of the nipple has internal screw threads whereby the converting device may be used to replace the dust cap of the steam radiator relief valve. A gravity operated valve 33 in the contracted neck, closes against the inflow of outside air but opens by pressure of the air inside the radiator when incoming steam is admitted.

50 In operation, the dust cap for the steam radiator relief valve air outlet is removed and the converting device is substituted in its stead. When the steam is admitted to the radiator, the air inside the radiator lifts the valve and escapes to the outside atmosphere. 55 The valve remains seated against the inflow of outside air after the steam is shut off, thereby maintaining a vacuum and establishing a vacuum radiator system.

60 It will thus be seen that the adjusting screw may be used to fix the normal position

of the thermostatic element and that the helical spring, which is interposed between the thermostatic element and the valve mechanism, will automatically prevent distortion of the thermostatic element after the valve 70 has seated and expansion of the thermostatic element continues. It will be obvious that the thermostatic element is positioned with respect to the bell-shaped base so that it is always above the water level whenever there 75 may be water therein.

The cupped ferrule serves the dual purpose of centering and locking the adjusting screw with the thermostatic element and provides the guiding and spacing means for the 80 inter-relative movement between the thermostatic element and the hood.

The means used to swedge the housing of the valve to the nipples and necks is simple, effective and economical in manufacture. 85

Although but one specific embodiment of this invention has been herein shown and described, it will be understood that numerous details of the construction shown may be altered or omitted without departing from 90 the spirit of this invention as defined by the following claims:

I claim:

1. A radiator relief valve comprising a 95 housing having a valve therein, a thermostatic element, said valve having a hood depending therefrom and surrounding the thermostatic element, means interposed between the valve and the thermostatic element adapted to prevent distortion of the 100 thermostatic element during its expansion, and a member embracing the thermostatic element and having a plurality of radially disposed outwardly projecting tongues adapted to slidily engage the inner side 105 of the hood during the inter-relative movement of the thermostatic element and the hood.

2. A radiator relief valve comprising a 110 housing having a valve therein and a thermostatic element adapted to close said valve during its expansion, a cupped ferrule adapted to embrace the thermostatic element, said ferrule having a radially disposed keyhole slot, the smaller aperture being concentric and the larger aperture being offset therefrom, and an adjusting screw 115 adapted for adjusting the normal position of the thermostatic element and having an annular groove intermediate its ends, said screw adapted to pass through said offset portion and be centered in said smaller aperture at said annular groove.

3. A radiator relief valve comprising a 125 housing having a valve therein, a thermostatic element, said valve having a hood depending therefrom and surrounding the thermostatic element, means interposed between the valve and the thermostatic element adapted to prevent distortion of the 130

thermostatic element during its expansion, a cupped ferrule embracing the thermostatic element and having a plurality of radially disposed outwardly projecting tongues 5 adapted to slidably engage the inner side of the hood and space the same with respect to the thermostatic element during the inter-relative movement between the hood and the thermostatic element, said ferrule having a radially disposed keyhole slot, the smaller aperture being concentric and the larger aperture being offset therefrom, and an adjustment screw adapted for adjusting the normal position of the thermostatic element 10 and having an annular groove intermediate its ends, said screw adapted to pass through said offset portion and be centered in said smaller aperture at said annular groove.

4. A radiator relief valve comprising a housing having a needle valved air outlet, a tubular thermostatic element, an inverted hood having a rod vertically projecting above and depending from its head, said vertically projecting rod being a needle 20 valve adapted to close the air outlet during the expansion of the thermostatic element, a flange headed tube interposed between and telescoping with said vertically depending rod and the thermostatic element, and a helical spring interposed between said flange 25

30

headed tube and the thermostatic element, whereby the thermostatic element will not become distorted during its expansion after the valve is seated.

5. A radiator relief valve comprising a housing having a valve therein, a tubular thermostatic element adapted to close said valve during its expansion, a helical spring interposed between the thermostatic element and the valve whereby the thermostatic element will not become distorted during its expansion after the valve is closed, a cupped ferrule embracing the thermostatic element and having a radially disposed keyhole slot, the smaller aperture of which registers with the bore of the thermostatic element and the larger aperture of which is offset therefrom, and an adjusting screw through the base of the housing adapted for the vertical adjustment of the thermostatic element having an annular groove intermediate its ends and above its screw threads adapted to pass through said offset aperture and be centered in said smaller aperture at said groove, the head of said screw telescoping with the bore of the thermostatic element.

Signed at Chicago this 17th day of May, 1926.

EMIL O. H. POEPPEL.
